2,640,485

MACHINE FOR SORTING AND SELECTING SHEETS OR PRINTED FORMS

Joseph Zalkind, New York, N. Y.

Application April 5, 1949, Serial No. 85,484

9 Claims. (Cl. 129—16.1)

1

This invention pertains to a machine for sorting and selecting sheets, printed forms, cards and like materials from a batch or stack, and has a particular application for sorting and selecting forms of the general type set forth in United States patents issued to the present inventor, Joseph Zalkind, said patents being No. 2,313,285 for a Sortable Multiple Form, issued March 9, 1943, and Patent No. 2,359,705 for a Machine for Sorting and Separating Sheets or Printed Forms, issued October 3, 1944.

Throughout the specification and claims, the words, "forms" or "sheets" may be used, and it is to be understood that the sheets or forms may be sheets of any material, printed forms, cards or the like, or any other filing element having distinguishing structural characteristics, such as slots, perforations, notches or the like to permit adequate keying of opposing end areas of the sheets or forms.

It is the object of the present invention to provide a machine for sorting and selecting sheets or forms by employing a novel means for sorting and/or selecting desired sheets or forms from a batch or stack of multiple forms. Frequently, the desired selection may be for the color of the form, the printed material on said form or other classified data, such as states, cities, counties and towns.

A further object of the invention is to provide a mechanism for sorting and/or selecting certain forms from a stack of forms and for withdrawing said forms from said stack by a novel and simplified operation.

A further object of the invention is the provision of a machine having adjustable guide means adaptable for forms of various dimensions, and wherein a novel selection device is operated to determine the form selected to be withdrawn from the stack of forms and a novel means for withdrawing the forms laterally from the stack to allow the selected forms to be removed by a single simplified operation.

A further object of the invention is to provide a sorting and selecting machine for sorting and selecting forms from a stack by employing a group of spindles adjacent opposing edges of the stack of forms and wherein the spindles, by a single operation, are moved into registry with the keyed portions of the forms on the opposing edges of the forms, and wherein a simple operation thereafter moves the selected forms to a position to facilitate removal of the selected forms from the stack.

A further object of the invention is the provision of a sorting and selecting machine which is simple in construction, has parts readily accessible for adjustment and is simple in operation.

A still further object of the invention is to provide a machine of the class set forth, having an inclined supporting member for the stack of forms so that there will be a reduced pressure between the adjacent forms from the weight of

the forms which would ordinarily exist if the stack of forms were normally disposed in a horizontal position, thereby facilitating aperture registry.

5 A still further object of the invention is the provision of a device of the class set forth, wherein novel means are provided for simultaneous multiple selection so that more than one type or group of selections may be made simultaneously and initially withdrawn from the stack of multiple forms by a single motion of the operator.

Further and other objects of the invention may be and may become apparent to one skilled in the art, and it is to be understood that the present disclosure is by way of illustration only of a preferred form of the invention. It is to be understood that changes and modifications may be made in the invention, and it is not intended that the invention should be limited except by the scope and spirit of the subjoined claims.

In the drawings,

Fig. 1 is a perspective view of the invention showing a stack of forms positioned on the machine, with the selected forms for the particular operation being partially withdrawn from a stack of forms.

Fig. 2 is an end view partially broken away of the machine shown in Fig. 1 with the stack of forms removed.

Fig. 3 is a sectional view taken substantially along lines 3—3 of Fig. 2, but with the lower form guide means being added.

Fig. 4 is a sectional view taken substantially along lines 4—4 of Fig. 3, showing one of the spindles being latched in position, and with an adjacent spindle being moved upwardly to replace the previously latched spindle.

Fig. 5 is a sectional view taken substantially along lines 5—5 of Fig. 3 to show the operating lever function in relation to the bevel gears for moving the carriage, and also for showing the means for adjusting the carriage for acceptance of forms which may have different dimensional characteristics than certain other forms.

Fig. 6 is a sectional view taken substantially along lines 6—6 of Fig. 4, but wherein the No. 3 spindle has been released and the No. 7 spindle is latched in its operative position.

Fig. 7 is a sectional view taken substantially along lines 7—7 of Fig. 3, showing the latch bar release in solid lines, wherein the selected spindle or spindles are latched in place, and also showing the latch bar release in dotted lines, wherein the latch bar is moved to release the previously latched up spindles carried by the carriage at the completion of a single operation of the operating lever.

Fig. 8 is a sectional view taken substantially along lines 8—8 of Fig. 7, showing the carriage riding on one of the bars of the carriage guide rails, and wherein the pulling spindles of the carriage are in registry with the transverse slots of the front panel.

Referring to the drawings, and more particu-

larly to Figs. 1, 2 and 3, there is shown the sorting and selecting machine 20 having a supporting structure 21 which consists of the base, back and end portions, which supporting structure has a front panel 22 secured thereon by screws 23.

The front panel 22 is shown having a selecting lever guide 24 secured on the outer surface thereof with slots, such as 25, formed therein to permit movement of the selecting levers, such as 26, which levers are used for selecting any pair of complementary spindles of which there are two main groups. One group of spindles are referred to as the holding spindles, are given character references from 1 to 8, while the complementary set of spindles, referred to as pulling spindles, are given character references 1A to 8A, respectively. There is a complementary sliding lever 26 for each of the cooperating pair of spindles, given character references 1B to 8B, respectively. For example, operation of the lowest selecting lever 1B shown in Fig. 1 would simultaneously cause holding spindle 1 and pulling spindle 1A to be urged upwardly through their respective apertures in the front panel. There is one aperture in the front panel for each of the holding spindles of which a representative aperture 27 is shown in Fig. 3.

The front panel, likewise, has formed therein apertures 28 which are in the form of transverse slots to permit lateral movement of the pulling spindles, such as 3A, shown in Fig. 1.

Referring particularly to Fig. 1, there is shown an end adjustment guide 29 and a bottom adjustment guide 30 so that the left edge of the stack of the forms may engage the end adjustment guide 29 to properly align the holes or slots in the left-hand end of the stack of forms with the row of holding spindles 1 to 8, respectively. The bottom adjusting guide 30 is used to lower and raise the stack on the inclined front panel 22 so that the holding spindles and pulling spindles will be properly aligned with their respective holes or slots for proper selection and sorting of the forms.

The pulling spindles 1A to 8A, respectively, are carried by a movable carriage 31 supported in a slideable carriage cradle 32 between opposing angular cradle guides 33.

The operating lever 34 when moved downwardly as shown by arrow X will cause the carriage to move to the right as may be seen in Figs. 1 and 3, so that any one or more of the pulling spindles will likewise be caused to move to the right and withdraw the corresponding selected forms from the stack, as shown in Fig. 1. At the completion of the downward movement of the operating lever 34, a spring 35 (Fig. 3) causes the carriage 31 to be moved to the left or restored to its normal position, and the operating lever 34 will likewise be returned to its normal inoperative position when it is moved in the direction of arrow Y.

The operation of any one of these selecting levers 26 is identical. Therefore, the operation of one lever will be described in detail with attention particularly directed to Figs. 3, 4 and 6.

A bracket 36 is secured in an inclined position between the base and back portions of the supporting structure. Elongated slots 37 are formed in the bracket, equi-distantly spaced for reception of the front holding spindles, such as holding spindle 5, shown in Fig. 3.

A latch guide plate 38, having a plurality of elongated slots therein, one slot corresponding

to each of the selecting levers, is secured to the bracket with the upper portion being bent to permit said guide plate 38 to be secured to the upper surface of the bracket by means of screws, such as 39. There is a plurality of apertures formed in the upper portion of the latch guide plate 38 to permit the holding spindles to be movably inserted therethrough. The lower portion 5 of the bracket 36 is secured to one side 10 of the bracket 36 by means of screws 40. The lower ends of the latch guide plate 38 are bent inwardly to form stop means 41 for the spindle latch 42. The lower end of each of these spindles has a reduced portion 43 which has the spindle latch 42 secured thereon and with a rubber stop 44 frictionally held on the end of each of the reduced portions 43.

An expansion spring 45 is movably disposed on each of the holding spindles with the upper end 20 of the spring engaging the bent portion of the latch guide plate 38, while the lower portion of the spring engages the upper surface of the spindle latch 42. The purpose of the spring is to normally hold the spindle in its retracted or inoperative position, as shown in Fig. 3.

The rubber stop 44 engages the guide pin control bar 46 and is intended to provide noiseless contact for engagement with the guide pin control bar 46. The latch bar 47 has a pair of slots 30 48 formed therein to permit headed studs 49 to be inserted therethrough and secured to the bracket 36, to permit lateral motion of the latch bar.

A spring 50 has one end thereof connected to 35 one of the studs 49 (Fig. 4) with the opposing end thereof connected to a flange 51 formed on the latch bar. Latch tongues, such as 52, having camming surfaces as shown, are formed on the lower portion of the latch bar with one tongue 40 being positioned for holding each of its respective spindle latches 42. When the guide pin control bar 46 is moved upwardly, the rubber stop 44 is engaged by said control bar and urges the spindle latch 42 upwardly until it engages the camming surface formed on the lower portion of the latch tongue 52, causing the latch bar to be moved to the left, as shown in Fig. 4, until the spindle latch 42 slides off of the camming surface and rests on the upper portion of the latch tongue 52, at which time the latch bar 47 will be urged to the right (Fig. 4) under influence of the spring 50 to cause the spindle latch to be retained in its uppermost position and locked in this uppermost or operative position by the latch bar.

It will therefore be seen that if two or more 55 selecting levers are simultaneously operated, and the control bars simultaneously urge their respective holding spindles to their operative positions, the respective spindles thus simultaneously operated will be latched in an operative position, which would be the case where multiple selecting was desired.

A latch bar release 54 has a portion protruding through the selecting lever guide 24 and is substantially rigidly connected to the latch bar. If the selecting levers be operated individually rather than simultaneously, i. e., in succession, then each spindle, as it is moved, will release the preceding spindle so that only the last actuated spindle will remain in the upper position. However, if for any reason it is desired to restore all of the holding spindles to their normal inoperative position, the latch bar release 54 may be pressed inwardly to cause operation of the latch bar and thereby release any spindle or spindles

so that they restore to their normal operating position.

Referring to the pulling spindles which are disposed on the carriage 31, the construction of said spindles in relation to the latch bar 47, the latch guide plate 38, the spindle latch 42, and the opposing upper and lower bent edges and the latch guide plate 38 are identical with the corresponding members shown in conjunction with the holding spindles. However, reduced portion 43 shown on the lower ends of the pulling spindles does not have a rubber stop, since the lower end of the pulling spindles is slightly spaced from the guide pin control bar 46 when the machine is in a normally inoperative position, as shown in Fig. 3.

The latch guide plate 38 for the holding spindles and the pulling spindles has the slots for the spindle latches open to the bottom thereof, so that the guide pin control bar 46 may engage the lower end of both the holding spindles and the pulling spindles with the upper portion of opposing ends of the guide pin control bar being inserted in the slots provided for the spindle latches to act as a guide means therefor. Each of the selecting levers 26 is L-shaped, having one end thereof terminating in a handle portion 55, which extends through the slots 56 formed in the selecting lever guide 24. The opposing end of each of said selecting levers is pivotally connected by a pin 57 to the guide pin control bar 46 somewhere in the middle portion thereof approximately as shown in Fig. 3. A stop pin 84 is secured to each of the selecting levers 26 and affords a limiting means for the left end of each of the guide pin control bars 46. A rubber stop 58 is placed on the lower portion of the carriage 32 so that all of the guide pin control bars 46 will noiselessly engage and rest thereon when the control bars are in the position as shown in Fig. 3.

A shaft 59 has opposing ends thereof held by a pair of arms 60 which are formed on the left side of the bracket 36. Cotter pins 61 are used on opposing end of the shaft, on the outer surfaces of the arms 60 to hold the shaft 59 in place. Spacers 62 (Fig. 6) are positioned between the adjacent selecting levers 26 to properly position and align said selecting levers in the machine. The selecting levers 26 are freely movable on the shaft 59, and under influence of springs 63 which are connected to the supporting structure and the selecting lever 26, assist in returning the selecting levers 26 to the normal position as shown in Fig. 3, at which time the guide pin control bar 46 is also returned to its normal position by gravity actuation, assisted by the influence of the spindle springs, such as 45. There is one spring, such as 63, for each of the selecting levers 26.

The carriage 31 has channel portions 64 formed longitudinally on opposing sides thereof, and each of said channels rides on its respective guide rail 65 to keep the carriage properly aligned and to permit said carriage to be moved from left to right so that the pulling spindle or spindles may be moved in their transverse slots 28 during the sorting and separating operation.

The latch-bar 47 carried by the carriage 31 has an automatic spindle restoring means which operates to restore any and all spindles to a normal position when the carriage moves to its extreme position toward the right of the machine, as shown in Fig. 3. A latch bar release 66 is secured to the latch bar 47 and has a camming surface thereon which engages the latch bar release stop 67 when the carriage is moved to its extreme position to the right. The latch bar release 66, shown in dotted lines in Fig. 7, indicates

that the latch bar 47 has been moved so that any of the spindle latches which were held upwardly, in their operative position, will be released when the carriage is moved to its extreme position to the right. The guide rails 65 are shown connected to the carriage cradle 32 by means of screws 68.

The operation of the carriage movement may be best seen in Fig. 5, wherein the operating lever 34 is shown secured to the shaft 69 by means of a pin 70. A threaded collar 71 is inserted through an aperture in the supporting structure and is secured thereon by a nut 72. A collar 73 is pinned to the shaft 69, but permits the shaft 69 to be freely movable by operation of the operating lever 34. A bevel gear 74 is slidably keyed to the shaft 69 by a key 75 and a spacer 76 slidably fitted on the shaft 69 assists in holding the gear 74, as shown in Fig. 5, so that the gear will slide on the shaft 69 when the carriage cradle is moved to and fro by rotation of the knurled member 81.

Another bevel gear 77 has the carriage lever 78 (Fig. 3) pinned thereto. A stud 79 is secured to a web portion 79 of the carriage 31. Both of said bevel gears are in engagement with each other. It will be seen that rotation or operation of the operating lever 34 in direction of the arrow X will cause the carriage to move to the right, due to rotation of the bevel gear 74 on the shaft 69. When the operating lever 34 is released, the spring 35 (Fig. 3) will draw the carriage lever 78 to the left, thereby causing the carriage to be restored to normal on the carriage cradle.

An adjustment screw 80 is threaded connected to the carriage cradle 32 with one end of said adjustment screw being rotatably mounted on an end member of the supporting structure and terminating in a knurled member 81, so that rotation of the knurled member will cause the carriage cradle 32 to be positioned relative to the holding spindles for acceptance of forms having varying dimensions.

The end adjustment guide 29 has slots formed on the opposing bent portions thereof so that headed screws 82 may be loosened or tightened as end adjusting guide 29 is positioned for the particular adjustment desired for an engagement of the stack of forms.

The bottom adjustment guide 30 has a headed screw 83 which slides in a slot 80 and terminates in a nut 84, which nut rides in a guide channel 85 secured to the underneath surface of the front panel 22. Guide slides 86 are formed in the front panel to stabilize and position the bottom adjustment guide 30 for the particular forms to be sorted and selected.

From the foregoing it will be seen that the present invention utilizes a unique means for the sorting or selecting of random or arbitrarily mixed forms, which forms may be of various dimensions, but on all forms there are openings including slots at the opposite edges wherein an aperture is utilized to retain certain forms in the stack by means of holding spindles, and a slot on the same edge to permit the selected sheets to be withdrawn from the stack. The opposite edge of the stack of forms has apertures for engagement by the pulling spindles of the selected group, or combination of groups or forms, with a series of slots or elongated slot transverse to the pulling end of the forms to permit the pulling spindle or spindles to move into their operative position and engage the apertures

of the selected forms to be withdrawn from the stack.

Further, there are adjustment guides for engagement with one edge of the stack of forms and for engagement with the bottom of the stack of forms. Both of said adjustment means being variable positionally to adapt them to the particular forms to be separated.

It is also pointed out that the inclination of the front panel while shown at one angle may vary in different adaptations of the machine, depending upon dimensional characteristics of the sheets or forms to be sorted or selected.

Further, from the foregoing, it will be seen that the machine for sorting and selecting forms utilizes a holding spindle mechanism and a pulling spindle mechanism, each of which has a plurality of spindles. Any pair of spindles consisting of one of the holding spindles and a complementary pulling spindle may be simultaneously operated by a selecting means which operates a control bar for urging the said pair of spindles upwardly to an operative position for engaging the forms selected to permit the pulling spindle to at least partially withdraw the selected forms from the stack of forms. The selected forms which may be selected by the simultaneous operation of two or more of the selecting levers permits multiple operation for sorting and selecting the particular forms or groups of forms desired. While the drawing of Fig. 1 shows the selected forms partially withdrawn from the stack of forms, it is to be understood that the selected forms may be completely withdrawn from the stack of forms, depending on the physical characteristics of the forms and/or the physical characteristics of the machine embodying the invention. The inclined supporting member or front panel 22, objectively set forth, is actually a loading rack or platform which may have any angular inclination or tilt to facilitate and assure proper registration or alignment of the apertures, such as slots and perforations in the forms, for the insertion of the holding and pulling spindles therethrough.

What is claimed as new and desired to be secured by Letters Patent by the United States is:

1. A machine for sorting and selecting forms, comprising a plurality of pairs of holding and pulling spindles, said pulling spindles being carried in a movable carriage, all of said spindles being reciprocal, and bars extending between respective pairs of spindles and engageable therewith, including means for selectively reciprocating said bars to simultaneously reciprocate respective pairs of said spindles, said bars being slidably related to said carriage and passing therethrough, whereby said carriage may be moved so as to effect motion of said pulling spindles with respect to said holding spindles.

2. A machine as set forth in claim 1, wherein said means for selectively reciprocating said bars comprises respective levers each terminating in a manually operable button at one end and in pivotal connections with respective bars at the other end.

3. A machine for sorting and selecting forms as set forth in claim 1, including detent fingers carried by said spindles and engageable with detent plates, there being a detent plate common to said holding spindles and a detent plate common to said pulling spindles, including means for effecting release of said detent plate from engagement with the respective spindles.

4. A machine for sorting and selecting forms as set forth in claim 1, including means for reciprocating said carriage comprising a pivot pin thereon, a rockable lever having a slot engageable with said pin, and means for rocking said lever.

5. A machine for sorting and selecting forms as set forth in claim 1, including an adjustable cradle reciprocatingly supporting said carriage, a rotative splined shaft, said cradle being adjustably movable with respect to said shaft, a driving member slidable on said shaft and rotative therewith and movable with said cradle, and means engaging said driving member and said carriage for transmitting motion therebetween when said shaft is rotated.

6. A machine for sorting and selecting forms comprising a base, a plurality of holding spindles carried by said base and reciprocal with respect thereto, a cradle carried by said base and slidably adjustable therein, a carriage carried in said cradle and slidably reciprocal therein, a plurality of pulling spindles mounted for reciprocation in said carriage, said holding and pulling spindles being aligned in pairs, and means for selectively reciprocating said pairs comprising a bar for each of said pairs and movable therewith, including means for actuating said bars to simultaneously reciprocate respective pairs of spindles, said bars passing slidably through said cradle.

7. A machine for sorting and selecting forms, comprising a plurality of holding and pulling spindles, said spindles having free ends and means providing axial reciprocal motion of said spindles, a table having a surface for supporting a pile of forms, said spindles being normally disposed on the other side of said table whereby said free ends may protrude reciprocally therethrough to engage perforations in said forms, there being openings in said table to accommodate said free ends, including means for transporting said pulling spindles with respect to said holding spindles, wherein said pulling and holding spindles are aligned in pairs, a pulling spindle and a holding spindle constituting each pair, and an actuating bar for each of said pairs disposed below said table and engageable with the lowermost ends of the respective spindles, including means for selectively moving said bars so as to effect protruding of the free ends of selected pairs of said spindles above the surface of said table.

8. A machine as set forth in claim 1, wherein said means for selectively reciprocating said bars comprises a bell crank lever for each of said bars, said levers terminating in pivotal connections with respective bars, including a base for supporting said levers and said bars, said levers having pivotal connections with said base and having portions extending beyond said base to provide access for manual operation.

9. A machine, as set forth in claim 8, including a stud on each of said levers engageable with respective bars for support thereof when said bars are at a rest position.

JOSEPH ZALKIND.
